UNITED STATES PATENT OFFICE.

EMIL HAEFELY, OF BASEL, SWITZERLAND.

PROCESS OF MANUFACTURING ELECTRIC INSULATING-SLEEVES.

1,237,031.

Specification of Letters Patent. Patented Aug. 14, 1917.

Application filed August 5, 1916. Serial No. 113,312.

To all whom it may concern:

Be it known that I, EMIL HAEFELY, a citizen of the Swiss Republic, and resident of Basel, Switzerland, have invented new and useful Improvements in Process of Manufacturing Electric Insulating-Sleeves, of which the following is a full, clear, and exact specification.

The employment of hard press-paper sleeves for insulation purposes in transformers is already known.

In the construction of transformers of modern types the windings are by preference fitted in annular form over the iron cores which, in order to adapt themselves to this form, are of rectangular or cruciform cross section. The low tension winding usually surrounds the core while the high tension winding surrounds the low tension winding, the latter being suitably insulated both internally and externally. Between the low and high tension windings insulation of high resistance corresponding to the difference of potential, is absolutely necessary; this insulation is generally constructed of hard press-paper cylinders of the requisite thickness which combine with very high insulating value the advantages of exact dimensions and high mechanical rigidity. Between the low tension winding and the iron however such a high resistance insulation is not generally necessary as the difference in potential is only comparatively low. Notwithstanding this however, a few factories employed hard press-paper cylinders in this position also in view of the convenience of erection and greater security, but of course they used cylinders of the smallest possible thickness. For reasons of manufacture however this thickness cannot be less than about 3 mm. so that the required degree of insulation is without necessity considerably exceeded and the cost of construction correspondingly increased. For the latter reason other manufacturers employ a more inferior insulating material for this purpose, for example sheets of pressed paper and the like are placed around the iron core. The resistance to penetration or breakdown of such materials is entirely sufficient for the purpose in view at the commencement; most of these materials have however all kinds of undesirable properties, such for example as liability to absorb moisture and so forth, so that it would be desirable to avoid their use in transformers if

the approved hard press-paper could be produced more cheaply.

The present invention relates to a process of manufacturing insulation sleeves of variable diameter, of hard press-paper, especially adapted for insulating purposes in transformers.

The insulation sleeves to be manufactured consist in the simplest form of at least one thin-walled tubular body of wound press-paper which is cut longitudinally and is under sufficient stress to cause the adjacent edges to overlap. In consequence of this construction the insulation sleeve can easily be forced into the required shape which it must have in a transformer and it is unnecessary to construct a sleeve of suitable dimensions for every individual case. For low and middle tensions it is recommended to employ at least one single sleeve or tubular body.

For higher tensions the insulation sleeve is preferably composed of a number of such tubular bodies which are inserted one inside another in such a manner that their longitudinal cuts are relatively displaced, the joint in one being covered by the solid portion of another tubular body. The number of tubular bodies used in this way depends upon the potential which the sleeve must be capable of withstanding. The tubular bodies may also be employed for a greater as well as for a smaller diameter than corresponds to their manufacture, inasmuch as they are slightly widened in the first case and slightly compressed with overlapping in the second case.

The improved process of manufacturing the insulating sleeves set forth consists in passing a web of paper coated with adhesive through a winding machine so as to wind up the separate layers and to cause them to stick together under pressure; each time after having thus united a determined number of layers to form a tubular body, a separating web or layer free from adhesive is allowed to pass in so as to effect a separation of the wound body or coil into sections or individual tubular bodies placed one around another, whereupon, after the cooling of the coil this is cut longitudinally and the sections or individual tubular bodies disposed one within another are separated at the webs or layers free from adhesive.

According to this process a thick-walled drum-like body or cylinder is produced

which constitutes a unit from a manufacturing point of view, and does not cause any difficulties in manufacture, whereas the thin-walled tubular bodies which have hitherto come into consideration as insulation sleeves can only be produced separately with difficulty and not of good quality. Furthermore, the said cylindric bodies may be stocked in the greatest sizes of manufacture and used afterward by being rolled up more or less, being thus brought into the cylindric shape required in any particular case.

In view of the present invention it is possible to employ hard press-paper, which is valued in consequence of its insulating capacity, and to make it comparatively cheaply in the required thickness and of good quality. It can therefore be used for example as insulation between two members of a transformer, as already hereinbefore described, either by pressing a cut tubular body to a smaller radius of curvature so as to cause the adjacent edges to overlap, which is easily possible in view of the inherent springiness of the tubular body, or by inserting two or more of the tubular bodies, according to the potential they are required to withstand, coaxially one within another in such a manner that the longitudinal slot of one is covered by the solid portion of the next inner or outer tubular body.

Obviously, the present invention is not only convenient for insulating purposes in transformers, but also as insulation on pole cores and the like, as well as for any insulating purposes in electric devices. Further, the cut tubular bodies which are thin-walled and flexible, although being obtained upon a mandrel of circular cross section, may also be employed upon cores, branches, bobbins and the like of any other form of transverse section, such as polygonal, oval, rectangular, square, etc.

The accompanying drawing shows three examples of the improved insulating sleeve; Figure 1 is a cross section of a sleeve composed of one single tube in use upon a transformer core; Fig. 2 is a cross section of a sleeve composed of two concentric tubes and Fig. 3 is a cross section of a sleeve composed of three concentric tubes.

According to Fig. 1, the insulating sleeve represented is composed of one single thin-

walled tubular body *a*, of wound-on or coiled press-paper, the layers of which are firmly united together by sticking and under pressure. The so formed body or tube is cut or split at *b* over its whole length and owing to its form and texture, it is springy or elastic within certain limits so as to allow its adjacent edges to overlap when it must be reduced in diameter, as represented.

Fig. 2 shows an insulating sleeve composed of two thin-walled tubular bodies, *c*, *d* of wound press-paper, cut over their whole length and each of which has its edges overlapped. The said tubular bodies *c*, *d* are concentrically arranged and so placed relatively to each other that their longitudinal slots and overlapping parts are angularly displaced, so that the slot of one is covered by a solid uncut portion of the other tubular body.

In Fig. 3 an analogous concentric arrangement is shown with three tubular bodies *e*, *f*, *g* of wound press-paper, cut over their whole length, but wherein the edges of each tubular body are not overlapped, but at some distance from each other, as shown, according to the greater diameter required for the insulating sleeve.

What I claim is:

A process of manufacturing longitudinally slit, springy insulation sleeves of variable diameter, of hard press-paper, consisting in mechanically winding up under pressure a web of paper coated with adhesive so as to unite the separate layers under pressure, and each time after having thus united a certain number of layers to form a tubular body, causing a separating web or layer free from adhesive to be wound on so as to separate the formed coil into sections or individual tubular bodies disposed one within another, then after the cooling of the complete coil cutting it longitudinally and finally separating the individual tubular bodies at the webs free from adhesive.

In witness whereof I have hereunto signed my name this 3d day of July, 1916, in the presence of two subscribing witnesses.

EMIL HAEFELY.
